PARACHUTE TOY

Thomas W. Newman, Columbus, Ohio, assignor
of ninety per cent to Fred W. Redding, Colum-
bus, Ohio

Application December 6, 1932. Serial No. 645,831

3 Claims. (Cl. 46—52)

This invention relates to toys and particularly to parachute toys of the species in which the parachute portion is connected with a pair of hollow hemispheres constituting a container for the para-
5 chute portion during the flight of the toy upward. In practice the parachute portion is folded or crumpled or compacted within the closed hemi-
spheres, these being temporarily held together when the toy is thrown upward into the air where-
10 upon the hemispheres open with the result that the parachute portion is liberated and expands and allows the toy to float slowly to the ground. A number of patents have been granted for such devices, but as far as I am aware such former
15 devices have been of such expensive construction as to preclude their retail sale for a sum, a dime for instance, within the reach of small children.

The object of the invention, therefore, is to provide a toy of the species referred to of improved
20 and simplified construction and improved mode of operation and which can be produced at a cost within the range of the buying power of children.

The invention is embodied in the example herein-
25 shown and described, the features of novelty being finally claimed.

In the accompanying drawing—

Fig. 1 is a view of the toy in side elevation accord-
ing to the invention showing the parachute portion liber-
30 ated from its container as after pro-
jection of the toy into the atmosphere.

Fig. 2 shows the container alone in cross section through the hemisphere connecting means.

Fig. 3 is a plan view looking at the concaved side of the parachute container structure.

35 Fig. 4 is a side elevation of the closed container looking toward the end of the hinge connection.

Fig. 5 is a similar view looking down on the hinge connection and with cord wrapped around the same to temporarily hold the parts of the
40 container in closed position as when throwing the toy into the air.

In the views 6, 6, designates the hollow hemi-
spheres forming the parachute container, said
parts being connected by a hinging portion 7.
45 These parts, according to the present invention are formed of soft or resilient rubber, all molded as one integral piece thereby avoiding the expense of making and assembling such parts as separate pieces. If desired the hemispheres are provided
50 with a slightly stiffening bead 8 around their rims, and the connecting hinge is left perforated, as shown at 9, to receive the attaching cord of the parachute portion. The hinge has a depression in its middle to permit the rims to fit closely together.

Exteriorly the hemispheres are provided with
ribs forming, when the hemispheres are closed, continuous grooves 10 and 11, the former for re-
ceiving several retaining coils of the parachute
cord 12 wrapped around the hemispheres to hold
them temporarily closed when the toy is in transit
upward into the atmosphere, and the latter groove
to receive an ordinary rubber band to hold the
cord 12 in wrapped condition as when the toy is
being carried in the pocket or displayed on a
sales counter.

13 designates the parachute proper which can be a square portion of flexible woven fabric of light weight, as for example silk, or imitation thereof, the four corners of said portion 13 hav-
ing each attached thereto a guy cord focused by
a knot 14 above the hinge to a single cord 12.
The single cord 12 is passed through the perfora-
tion of the hinge and constitutes the means for
wrapping around the hemispheres in the groove
10 to hold the hemispheres temporarily together,
said cord being provided with a knot 15 spaced
sufficiently from the knot 14 to allow play of the
hinge between said knots, said knots constituting
stops to limit the play.

The cord 12 is provided at its end with a small weight 16, preferably of lead, which promotes the unwinding of the cord from the ball when thrown into the atmosphere, said ball, of course, rotating when it is thrown.

17 designates a cord, elastic if desired, attached at its ends to the opposite outer edges of the two hemispheres to extend diametrically across the concave sides of the hemispheres when the latter are in extended or open position. Said cord, 90 when the hemispheres spring to open position, straightens and tends to expel the parachute proper from the container.

By reason of the integrality of the hemispheres with the hinging portion the container is eco-
nomically manufactured in a mold and the hemi-
spheres resiliently normally held in an open po-
sition approximately that shown in Fig. 2. By
reason of the resilient hinge the hemispheres
when released from a closed position automatical-
ly resume the open position and such automatic
opening of the container and straightening of
the cord effects the ejection of the parachute
proper as set forth.

In use the toy is thrown into the air with the 105
parachute proper inclosed in the hemispheres held together by the cord 12 only, which in the
course of the flight becomes unwound and re-
leases the parachute as shown in Fig. 1 permitting
the toy to float to the ground.

The forms of the parts can be changed without departing from the gist of the invention as claimed.

What I claim is:

- 5 1. In a parachute toy, a container for the parachute proper comprising closable container sections having resilient means hingedly connecting them, said resilient means constructed to yieldingly hold said container members normally in open position and a parachute ejector-means consisting of a string connected with the outer opposite portions of said container members of such length as to be tightened by the opening of the container members.
- 10 15 2. In a parachute toy, a container for the parachute proper of resilient material including hol-

low matching parts having integral therewith a hinging connection between them also of resilient material, said hinging connection provided with a perforation for the passage and retention of a container winding parachute holding cord.

80

3. In a parachute toy, a container for the parachute proper including a pair of hollow matching parts of substantially hemispherical form and a hinging connection for said parts between the bases of said hemispheres, said hemispheres and their hinging connection being of resilient material and integral with one another whereby said hemispheres are normally and yieldingly held in open and extended position.
